TIMER

Rex C. Darnell, Dexter, Mich., assignor to King-
Seeley Corporation, Ann Arbor, Mich., a cor-
poration of Michigan

Application May 17, 1946, Serial No. 670,612

2 Claims. (Cl. 161—23)

1

The present invention relates to timers of the type which are used to time the cycle of operation of any apparatus such as a stove, washing machine or the like, and which are operative either to initiate or terminates an operating cycle after a predetermined time interval or to actuate a signal device for the guidance of the operator.

One of the objects of the present invention is to provide in a timer of the type mentioned an improved signal actuator cocking and tripping mechanism.

Another objection is to provide a cocking and tripping mechanism for the signal actuator which will relieve the main arbor of the timer of the frictional load incident to holding the actuator in cocked position.

Another object of the invention is to provide in a mechanism of the type mentioned means for adjusting the tripping point of the mechanism with reference to the rotational position of the main arbor.

Another object of the invention is to provide an improved mechanical limit stop mechanism for limiting rotation of the arbor in both directions.

A further object is to provide means for recocking the actuator in the event that it is accidentally tripped while the timing arbor is out of tripping position.

A further object is to provide improved means for rendering the timing mechanism inoperative in one position of the arbor.

Other objects and advantages of the invention will become apparent from the following specification, the accompanying drawings and the appended claims.

In the drawings:

Figure 1 is an elevation view of the timing mechanism with the outer casing and one of the movement plates removed to show the interior construction;

Figure 2 is a view similar to Figure 1 with only the casing removed, showing the mechanism mounted on the exterior of one of the movement plates;

Figure 3 is a view similar to Figure 1, showing the parts in a different position; and

Figures 4 and 5 are fragmentary views showing a portion of the mechanism on an enlarged scale.

Inasmuch as the type of timer to which the present invention relates may to a large extent be conventional in construction, only so much of the details of construction are shown as are necessary to fully understand the features of the

2

present invention. For further details of one suitable type of timer to which the present invention relates, reference may be had to applicant's copending application, Serial No. 659,764, filed April 5, 1946. It is sufficient to note here that the mechanism ordinarily comprises a casing containing any suitable form of clock mechanism mounted between a pair of movement plates in the usual manner and a spring operated signal actuating device which is cocked when the timer is set to the desired timing cycle and which, when tripped, either rings a bell or operates an electrical switch.

In the type of timer construction to which the present invention relates, the main arbor of the clockworks is provided with a manual control knob and the arrangement is such that when the arbor is rotated in one direction from zero or starting position, the signal actuator is cocked. The rate of return of the arbor to starting position is controlled by the clock mechanism, and the actuator is tripped upon return of the arbor to starting position, thus operating a signal, an electrical switch or other suitable device.

Referring to Figures 1 and 2, the mechanism of the present invention is shown incorporated in a timer having a clock mechanism carried by and between a pair of movement plates 1 and 2. The clock mechanism includes a main arbor 3 suitably journaled for rotation with respect to the movement plates and connected in the usual manner through a train of gears to a verge-type escapement comprising an escape wheel 4, a verge arm 5 and a balance wheel 6 carried by a balance staff 7. A mainspring, not shown, associated with the arbor 3, normally tends to rotate the arbor in a clockwise direction, as viewed in Figures 1 and 2, under control of the escapement mechanism and associated gear train in the usual manner.

As best shown in Figure 1, the movement plate 1 carries a pivot pin 8 upon which is pivoted a signal actuator which, in the illustrated form of the invention, comprises a bell hammer 9. The actuator 9 is normally urged in a clockwise direction about the pin 8 by means of a relatively stiff spring 10, one end of which is hooked at 11 over a notch in the movement plate 1 and the other over a projection 12 on the actuator lever 9.

The actuating member 9 is provided with a rearwardly projecting arm 13, which is pivotally connected by a pin 14 to a toggle link 15, which, in turn, is connected by means of a pin 16 to one end of a U-shaped lever 17. The central portion of the U-shaped lever is pivoted on a

pin 13 carried by the movement plate 1, and the opposite end of the lever is provided with a roller 19, which projects through an arcuate slot 20 in the plate 1, as best shown in Figure 2.

The actuating lever 9 and the connected linkage are illustrated in Figure 1 in the tripped position which they assume after the arbor 3 is returned to its starting or zero position and the mechanism has been tripped. It will be observed that the spring 10 urges the mechanism into the position illustrated in Figure 1, in which position the parts are held against further movement by engagement of roller 19 at the end of the slot 20.

In order to prevent tilting of the U-shaped lever 17 with respect to a plane parallel to the movement plates, the lever is provided with a projecting arm 21, the outer end of which is bent toward and engages the inner surface of the movement plate 1 adjacent its periphery. This is necessary inasmuch as the end of the U-shaped lever which is connected to link 15 is offset with respect to the main body of the lever 17 and lies in a plane spaced at a greater distance from plate 1 than does the main body of the lever.

As best shown in Figure 2, the mechanism for cocking the actuating lever 9 comprises a spiral cam disk 22 having a more or less radial flange 23 which is bent toward the movement plate 1 into the plane of the roller 19 on lever 17. As a result of this arrangement, counterclockwise rotation of the arbor 3 will cause the flange 23 to engage the roller 19 and force the latter downwardly in the slot 20, as viewed in Figure 2. This swings the lever 17, link 15 and the actuating lever 9 into the cocked position illustrated in Figure 3.

It will be observed that in the cocked position, the toggle linkage has been swung slightly past dead center inasmuch as pin 16 is located slightly to the left of a line connecting the axes of pins 14 and 18. It will be apparent, therefore, that when the flange 23 of the cocking cam 22 forces the roller 19 downwardly in slot 20 sufficiently to swing the toggle linkage to a slight extent past dead center, the spring 10 will then act to carry the toggle linkage to a further extent past dead center, thereby shifting the roller 19 entirely out of engagement with the cocking cam 22.

This cocking movement is finally limited by engagement of the roller 19 with the lower end of the slot 20, as viewed in Figure 2, at which time the parts assume the position shown in Figure 3. Under these conditions the spring 10, instead of tending to effect a tripping operation, actually serves to hold the actuating lever 9 in cocked position. However, in order to trip the mechanism, it is only necessary to shift the pivot pin 16 slightly past its dead center position in the opposite direction, whereupon the spring 10 will actuate the lever 9 to operate a signal or switch.

Means are provided for shifting the pivot pin 16 from its over-center position of Figure 3 in order to trip the actuating lever upon return of the arbor to starting position by the clock mechanism, and this means is combined, in accordance with the present invention, with mechanism operative to positively limit rotation of the arbor in both directions. This mechanism, as best shown in Figure 2, comprises a lever 24 pivoted by means of a pin 25 on the movement plate 1 and a second lever 26, which is connected to the lever 24 by means of a frictional rivet 27. The rivet 27 is so constructed that it pivotally con-

nects the levers 24 and 26 but holds them in tight frictional engagement with each other, with the result that they cannot be angularly displaced with respect to each other except by exertion of a substantial force.

In the region in which the levers 24 and 26 overlap, lever 24 is provided with a small circular opening 28, which is aligned with the center of a slot 29 in the lever 26. When it is desired to adjust the angular position between the levers 24 and 26, such adjustment is effected by inserting into the slot 29 the end of a circular rod-like tool having a diameter equal to the width of the slot 29 and having a projecting eccentrically located pin, the axis of which extends parallel to the rod and which is adapted to fit the opening 28. After the pin on the end of the rod-like tool is fitted in the opening 28, the tool is rotated and, by reason of the eccentric location of the pin, the tool will shift the angular position of lever 26 relative to that of lever 24, as desired.

Lever 24 is provided with a projection 30, which extends through a suitable opening formed in the plate 1 and into the path of the toggle link 15.

Lever 26 is provided with a flange 31, which projects in the opposite direction into the path of movement of the flange 23 on cam 22. Lever 26 also is provided with a projecting right-angled arm 32 adapted to engage a stationary pin 33 carried by the movement plate 1. The arm 32 is normally held in engagement with the pin 33 by means of a spring 34, which is wrapped around the pins 25 and 27 and has its free end engaging the pin 33 in such a manner as to tend to cause a rotation of the levers 24 and 26 in a counterclockwise direction about the pin 25, as viewed in Figure 2. As a result of this construction, counterclockwise rotation of the levers 24 and 26 about the pin 25 is limited to the position shown in Figure 2 and, consequently, when the arbor returns to its starting position, as indicated in Figure 2, the flange 23 on the cam 22 will engage flange 31 on the lever 26. This will positively limit further clockwise rotation of the arbor and thus bring the timer to a stop in its zero position. It will be observed that the positive stop thus provided does not involve the exertion of any force on the levers 24 and 26 tending to cause a relative rotation of one of the levers with respect to the other about the friction rivet 27.

During the return movement of the arbor to zero position under the influence of the clock mechanism, the toggle lever 15 will be in engagement with the projection 30 of lever 24, as illustrated in solid lines in Figure 3, thus holding the arm 32 of lever 26 out of contact with the stop pin 33. As the arbor approaches its zero or stop position, flange 23 of cam 22 engages flange 31 on lever 26 and thus swings levers 24 and 26 about the pin 25 in a counterclockwise direction. This swings the projection 30 on lever 24 from the solid line position shown in Figure 3 to the dotted line position shown in the same figure, thus shifting toggle link pin 16 over the dead center position and thereby tripping the actuating lever 9. By this time the cam 22 will be in approximately the position shown in Figure 2, thus permitting return of roller 19 to the upper end of slot 20. Immediately after the tripping operation occurs, arm 32 on lever 26 engages the stop pin 33 and thereby stops further clockwise rotation of the arbor. The angular adjustment provided between the levers 24 and 26, as previously described, thus permits an adjustment of the distance between the projection 30 and the

flange 31 and thereby adjusts the point in the return movement of the arbor at which the tripping action occurs. This adjustment is desirable to correct for variations in the tripping point resulting from the unavoidable tolerances in manufacture.

The period of time through which the timer operates depends upon the degree of angular counterclockwise rotation of the arbor 3 during setting, the maximum period corresponding to a 10 rotation of the arbor through an angle of approximately 360°. The previously described mechanism operates to positively limit setting movement to a maximum angle of 360°. This results from the fact that upon a counterclockwise rotation of arbor 3 from the position shown in Figure 2, the flange 23 on the cam 22 will eventually engage the rear side of the flange 31 on lever 26. Such engagement swings the lever 26 and its associated lever 24 in a clockwise direction about the pin 25 until the flange 31 engages the stop pin 33. This effects a positive abutment which will prevent further counterclockwise rotation of the arbor. Again it will be noted that this limited abutment is so constructed that the forces imposed upon it do not tend to cause any relative rotation between the levers 24 and 26. Moreover, it will be noted that since lever 26 has a lost motion relationship with respect to the stop pin 33, a full 360° rotation of the arbor between its two limiting stops is provided.

For some purposes it is desirable to provide means for preventing unwinding rotation of the arbor after it has been rotated in a setting direction to the maximum extent. Such an arrangement is advantageous, for example, when the timer is utilized to operate a switch which terminates the cycle of operation of a machine. In that case, when it is desired to operate the machine continuously or for a period in excess of that provided by the timing mechanism, the arbor may be rotated through its maximum setting movement, whereupon the timing mechanism will be locked, with the result that no unwinding rotation occurs until after the arbor is manually displaced from its maximum position. As best shown in Figure 2, means for this purpose are provided comprising an arm 35 pivoted on plate 1 by a pin 36. The terminal portion 37 of the arm 35 is normally held in a position bearing against the arbor 3, in the manner best shown in Figure 4, by means of one end 38 of a wire spring which is clamped to the arm by means of a bent-over tab 39 and which bears against a bent-up lug 40 on the movement plate. The opposite end 41 of the spring projects in a direction generally parallel to the arm 35 and is bent at right angles in such a manner as to enter a slot 42 formed in the movement plate 1, the inwardly bent end being normally located in the position indicated in Figures 1 and 3 at a point spaced to a slight extent from the periphery of the balance wheel 6 of the escapement mechanism.

The arbor 3 is provided with a notch 44 which assumes the position relative to the terminal portion 37 of the arm 35 which is illustrated in Figure 4 when the arbor is in its zero or stop position. In order to set the timer, the arbor 3 is rotated in a counterclockwise direction, as viewed in all figures of the drawings, and it will be apparent from Figures 4 and 5 that upon completion of a counterclockwise rotation through an angle of 360°, the notch 44 will carry the terminal portion 37 of the arm 35 into the position

shown in Figure 5. This permits the arm 35 to swing in a counterclockwise direction, as viewed in Figure 2, under the influence of spring 38, thereby pressing the end 41 of the wire against the periphery of the balance wheel. A very light pressure between the wire and the balance wheel is sufficient to prevent operation of the clock mechanism and, consequently, return of the arbor to its zero position. The timer will, therefore, remain in its maximum setting position indefinitely.

When it is desired to return the arbor to its zero position, either manually or under the control of the clock mechanism, the arbor is simply rotated in a clockwise direction through a very small angle sufficient to swing the arm 35 in a clockwise direction, as viewed in Figure 2. This disengages the wire 41 from the balance wheel and permits operation of the clock mechanism. An important feature of the full wind holding mechanism above described resides in the fact that it permits a full 360° rotation of the arbor from the zero position to the full wind position and yet causes operation of the holding mechanism only when the arbor is in its full wind position. This results from the fact that the terminal portion 37 of the arm 35 can only enter the notch 44 and be swung to the holding position illustrated in Figure 5 upon a counterclockwise rotation of the arbor, as viewed in Figure 5, to the position shown in Figure 5. Rotation of the arbor in the opposite direction into the same position does not permit entry of the terminal portion 37 into the notch. Consequently, the holding means does not stop the clock mechanism at or near the end of the unwinding movement. This is desirable since otherwise it would be necessary to accurately correlate the operation of the holding mechanism with the zero point on the timer dial and the point of actuation of the signal actuator.

It should be noted that the cocking cam 22 has a peripheral surface lying in a generally spiral path beginning and ending at the cocking flange 23. As a result of this form, the actuating mechanism or hammer 9 may be recocked by a reverse or clockwise rotation of the arbor 3, as viewed in Figure 2, in the event that the hammer mechanism is accidentally tripped before the cocking cam returns to its tripping or zero position. In that case, it should be noted that if the timer is dropped or subject to a severe jar when the hammer mechanism is cocked, the toggle linkage may be jarred over the dead center position and thereby tripped while the arbor was in its full wind or a partially wound position. In that case, in the absence of the spiral peripheral cam surface on the cocking cam, it will be impossible to return the arbor to its zero position and, therefore, impossible to restore the timer to an operative condition. It will be appreciated that in the construction illustrated, after such an accidental tripping of the actuator 9, the roller 19 will move upwardly in the slot 20, until it moves into contact with the spiral-shaped peripheral surface of the cam disk 22 which it will be appreciated will be turned in a counterclockwise direction, as viewed in Figure 2, during the cocking and setting of the timer. The actuator 9 may be recocked by rotating the disk 22 in a clockwise direction, as viewed in Figure 2, during which movement the roller 19 is positioned downwardly in the slot 20 to its cocked position by the spiral-shaped peripheral surface of the cam disk 22. If this feature of

the invention is not desired in any case, the cocking cam need only constitute a radially projecting arm carrying the flange 23.

While only one form of the invention is shown and described herein, it will be apparent that variations in the design and details of construction may be indulged in without departing from the spirit of the invention or the scope of the appended claims.

What is claimed is:

1. In a timer having a frame, a spring operated signal actuator, means for holding said actuator in a cocked position, a rotatable arbor adapted to cock the actuator and render said means operative to hold said actuator in said cocked position on rotation in one direction from a starting position, a member pivoted on the timer frame independently of the arbor and adapted to render said means inoperative to hold the actuator in said cocked position, a second member, means 20 adjustably mounting said second member on the first member, abutment means on the timer frame adapted to engage said second member and thereby limit pivotal action of said members in both directions, and means on the arbor adapted to 25 engage said second member at the end of a predetermined degree of rotation of the arbor in said one direction and at the end of a return rotation to starting position whereby said second member provides a positive stop in both directions of rotation, said second member being adapted to engage said first named means to cause a tripping movement of the first member as it is moved against said abutment means on return of the arbor to starting position.

35

2. In a timer having a frame, an arbor rotatably mounted on said frame, a spring operated signal actuator mounted on said frame, means on the arbor for engaging and cocking said actuator when said arbor is rotated away from starting position, means mounted on said frame adapted to engage said last named means for limiting the rotation of the arbor, means mounted on said arbor for tripping the actuator on return of the arbor to starting position, and means mounted on said arbor and operable in the event that the actuator is accidentally tripped while the arbor is displaced from the starting position, in response to movement of the arbor toward starting position, to engage and recock said actuator whereby the actuator is placed in proper position to cooperate with the tripping means.
